(57) **CLAIM**

The ornamental design for an LED whip light, as shown and described.

DESCRIPTION

FIG. 1 is a front, right and bottom perspective view of an LED whip light, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of portion 9 shown in FIG. 1; and, FIG. 10 is an enlarged view of portion 10 shown in FIG. 2. The dashed broken lines shown in the drawings illustrate portions of the LED whip light that form no part of the claimed design.

The dot-dash broken lines framing portions of the claimed design are included for the purpose of illustrating enlargements, and form no part of the claimed design.
